UNITED STATES PATENT OFFICE

2,215,311

ELECTRIC SWITCH

Charles A. Adams, Davenport, Iowa

Application November 20, 1937, Serial No. 175,678

1 Claim. (Cl. 173—346)

The present invention pertains to electric switches, broadly, and more specifically to socket switches, operable by pressure upon a side of the switch body, as in the case of the British 5 Patent No. 2,325 of 1899. Among the objects of this invention are to provide a switch which is easily assembled and inexpensive to manufacture; to provide a switch in which the switch parts are enclosed in a moisture-proof casing; 10 to provide a switch having no operating part projecting through the casing and capable of carrying current to the hand of the user of the switch; to provide a switch of the type indicated which is hermetically sealed to prevent entrance of explosive gases; and such further objects, advantages, and capabilities as will hereafter appear and as are inherent in the construction disclosed herein. My invention further resides in the combination, construction, and arrangement of parts 15 illustrated in the accompanying drawing and, while I have shown therein what is now regarded as the preferred embodiment of this invention, I desire the same to be understood as illustrative only and not to be interpreted in a limiting sense. 20 25

In the drawing annexed hereto and forming a part hereof,

Fig. 1 represents a longitudinal sectional elevation of a construction embodying my present invention, the same being represented as taken 30 approximately along the plane indicated by the line 1—1, Fig. 2;

Fig. 2 represents a transverse section substantially along the plane indicated by the line 2—2, Fig. 1;

Fig. 3 represents a longitudinal sectional elevation of a modified form of my construction, the same being represented as taken substantially along the plane indicated by the line 3—3, Figs. 4 and 5;

Fig. 4 represents a transverse section taken approximately along the plane indicated by the line 4—4, Fig. 3;

Fig. 5 represents a transverse section taken approximately along the plane indicated by the line 5—5, Fig. 3; and

Fig. 6 represents the application of one form of my invention in a switch not provided with a lamp socket.

Reference will now be made in greater detail 50 to the annexed drawing for a more complete description of this invention. The switch casing is formed from a pair of similar, moulded rubber sections 1 and 2 which are so shaped that when placed face to face and cemented together or cemented and vulcanized together they will con-

stitute a casing for the switch parts, which casing will be fluid-proof so as to prevent short circuiting of the switch or conduction of current from the live wire to the hand of the user of the switch. The sections 1 and 2 are provided with channels 5 for the reception of the conducting strips 3, 4, and 5 which fit very closely in the channels and may even be cemented therein. A switch operating member 6 has one end embedded in the casing and has its other end turned at a right angle, as 10 shown at 7, to engage projections 8 on the current conducting disc 9 which is mounted on and is rotatable about the axle 10.

The casing is tubular in form and has one end closed, as indicated at 11, and has a socket 12 15 in its opposite end for the reception of the threaded metallic current conducting sleeve 13 into which the threaded base of an electric lamp is to be screwed. One end of the conducting strip 5 terminates within the sleeve 13 and is bent over 20 in the customary manner to engage the center contact of a lamp bulb screwed into the socket 13. The strip 3 and socket 13 are secured together by soldering or brazing before assembly 25 of the parts of the switch so that when the metal parts are inserted in the cavities of the rubber blocks no further work will need to be done upon these metal parts in order to be ready to assemble and unite the parts of the casing. The conducting strip 4 has an end bent over, as indicated 30 at 14, and to this, one end of the wire 15 is secured by the screw 16. The end of the wire 17 is secured to the bent over end of the strip 3 by the screw 18.

The cavity 19 is separated from the cavity 12 35 by a wall 20, made up of parts integral with the two sections 1 and 2. The wall 20 is undercut, as indicated at 21 in Fig. 1, to give greater flexibility of the casing on the side adjacent the member 6. A knob or finger piece 22 is formed on 40 the outside of the casing to indicate where pressure is to be applied for the actuation of the member 6 by means of which the disc 9 is rotated.

A plurality of notches 23, preferably eight in 45 number, are formed in the edge of an insulating disc 24 to be engaged by the inner ends of the strips 4 and 5. The conducting disc 9 has arms 50 25, half as numerous as the notches 23, and these arms occupy alternate notches 23 in the edge of the disc 24. It is obvious that these parts can be arranged in various ways to accomplish the same purpose and I therefore do not wish my claim to be limited to the particular structure herein disclosed. When it is desired to operate the 55

switch, one presses on the knob 22, forcing the side of the container inwardly against the member 6 and flexing this to cause the end 7 to engage, an abutment 8 whereby to force the disc 9 to rotate on its axle 10. When it does this, the ends of the strips 4 and 5 yield, permitting the projections 24 to pass under them so that the ends of the strips engage in the next succeeding notches. These strips then hold the disc against backward rotation when the pressure on the knob 22 is released. Various other similar modes of operating the ratchet disc in which the notches 23 are cut may be employed without departing from the spirit of this invention. For example, the member 6 may be much shorter and nearly straight, with its outer end extending through the wall and into the knob 22 so that the member 6 will be yieldably mounted and will move with the movable portion of the wall of the container.

A small flange 26 is formed around the end of the switch container remote from the socket end and a unitary cap 27, having a flange to engage the flange 26, is provided and snaps over the end of the container to enclose the ends of the wires 15 and 17 and the screws 16 and 18. Because of this arrangement, it is impossible for the hand of the user to come in contact with any metal current-carrying part or to contact any wet part capable of carrying a current whereby the user might get an electric shock.

Instead of having the grooves for the strips 3, 4 and 5 formed in mating grooves in the two parts 1 and 2, it is possible to form these grooves deeper and entirely in one part so that the edges of the metal strips will come just flush with the flat face of the rubber part and then the other rubber part will act as a cover for the openings in the first part. The parts 1 and 2 may be merely cemented together or they may be cemented and vulcanized. It is regarded as important that these parts shall be more or less permanently united in such a manner as to be substantially proof against fluid entering the chamber 19.

In a large measure, the structure shown in Figs. 3, 4, and 5 is similar to that shown in Figs. 1 and 2, but there are certain minor variations, all being connected with the bridging member between the contact strips and the means for actuating this bridging member. In the construction shown in Figs. 3, 4, and 5, a lever 28 is pivoted at 29 and may be rocked on its pivot, as is obvious from Fig. 3. In Fig. 3, the strips 4 and 5 are denoted by the numerals 4a and 5a because of the fact that they differ somewhat in shape from the corresponding elements of the previously described construction. The lever 28 has a post 30 projecting transversely from its middle

portion and this post has a small central projection at its end which extends into a spring 31, the opposite end of which engages the inner face of the wall forming the opposite side of the chamber 19 from that which is pressed to cause actuation of the switch. When pressure is exerted on the knob or projection 22a, rocking of the lever 28 about its axle 29 is caused, and the switch has more or less of a snap action, due to the connection between the parts 30 and 31 passing a dead center. Pressure upon the knob 22b will cause rocking of the lever 28 in the opposite direction to cause closure of the switch, as illustrated in Fig. 3. A bent metal piece 32 prevents the piece 4a from working outwardly, even if the cement should fail to hold it rigidly connected to the rubber.

The structure shown in Fig. 6 is similar to that shown in Fig. 1 with the lamp socket omitted and other minor changes made. In this form, the strips 3 and 5 are joined into one and the actuator member 6 is replaced by an element 6a embedded in the knob 22, as suggested above. Otherwise, the structure is unchanged. This structure may be further modified by forming a flange 26 at each end of the body shown in Fig. 6 and applying a cap 27 to each end. The central contact in the lamp socket, as shown in Fig. 1, would be shortened and bent in against the wall 20, and the end of strip 3 would likewise be bent 30 against the wall 20. Screws comparable to 16 and 18 would be provided for the attachment of wires to the strips 3 and 5. This arrangement would include the switch in one wire only of a pair of wires.

It will of course be understood that the specific description of structure set forth above may be departed from without departing from the spirit of this invention as set forth in this specification and the appended claim.

Having now described my invention, I claim:

An electric switch comprising a substantially unitary fluid-proof hollow rubber body, a pair of circuit terminals extending through the wall of said body and into the hollow in said body, and a contact member having two normal rest positions, in one of which it makes electrical contact with said terminals and in the other of which it is out of electrical contact with said terminals, said contact member comprising a rotatable element having a notched edge, one pair of notches being out of electrical contact and another pair of terminal engaging notches being in electrical contact, a section of the wall of said body being operative upon flexure into the hollow to shift said contact member from either of said positions to the other.

CHAS. A. ADAMS.
